US00D794654S

(12) **United States Design Patent** (10) **Patent No.:** **US D794,654 S**
Sung et al. (45) **Date of Patent:** **** Aug. 15, 2017**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Sophia H. Sung**, Irvine, CA (US); **Jonathan P. Gaiser**, Sunnyvale, CA (US); **Chris Turkstra**, San Jose, CA (US); **Maxel J. Keene**, Sunnyvale, CA (US); **Heejin Ko**, Bucheon-si (KR); **Jangwon Seo**, Seoul (KR); **Jae Julian**, Seoul (KR); **Yoojin Choi**, Seoul (KR)

(73) Assignee: **SAMSUNG ELECTRONICS CO., LTD.**, Suwon-si (KR)

(**) Term: **15 Years**

(21) Appl. No.: **29/550,218**

(22) Filed: **Dec. 31, 2015**

(51) LOC (10) Cl. **14-04**

(52) U.S. Cl.

USPC **D14/485**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The broken lines in the drawings illustrate portions of the display screen with a graphical user interface that form no part of the claimed design.

1 Claim, 1 Drawing Sheet
